METHOD AND APPARATUS FOR FEEDING
AND PRINTING PAPER

Fred R. Bartholomew, Minneapolis, Minn.

Application September 19, 1946, Serial No. 697,846

9 Claims. (Cl. 101—132.5)

1

This invention relates to a novel method and apparatus for dampening paper as it is fed into duplicating or printing machines. This method and apparatus may be used to feed paper into different types of printing and duplicating machines but it is particularly adapted to feeding paper into those duplicating machines that require the paper be dampened as it is fed into the duplicating machine.

It is therefore an object of this invention to provide a simple and efficient method and apparatus that feeds paper into a duplicating or printing machine and at the same time dampens the paper, when required, as it is fed into the duplicating machine.

It is a further object of this invention to provide a simple and efficient method and apparatus for printing or duplicating in which a continuous length of a pliable lithographic plate, or a stencil, or other flexible means with the image thereon in reverse is used and into contact with which the paper or other material to be printed on is brought.

It is a further object of this invention to provide a method and apparatus in which a continuous flexible member having separated ends is used, the same having the image to be printed thereon in reverse and into contact with which paper which has been dampened is brought for printing.

It is further an object of the invention to provide a method and apparatus comprising the use of printing members, an endless gelatin film adjacent said printing members, and means for moistening said film, said film being arranged to contact, feed and moisten paper to be passed between said printing members.

It is further an object of the invention to provide a method and apparatus comprising the use of printing members and a continuous flexible sheet of material having the image thereon in reverse in hectograph ink, one end of which sheet is passed between said printing members into contact therewith and which is then drawn between said printing members, a dampened sheet of paper being placed between said sheet and said printing members for printing.

It is still another object of the invention to provide a method and apparatus such as set forth in the preceding paragraph in which a roller is provided on which said sheet is wound as it is drawn between said printing members, said sheet preferably being unwound from another roller before passing between said printing members.

2

These and other objects and advantages of the invention will be fully set forth in the following description made in connection with the accompanying drawings in which like reference characters refer to similar parts throughout the several views and in which:

Fig. 1 is a view in side elevation of an apparatus used for carrying out the method of this invention;

Fig. 2 is a view in end elevation as seen from the left of Fig. 1;

Fig. 3 is a view in end elevation as seen from the right of Fig. 1;

Fig. 4 is a view in side elevation of a modification showing a flat bed press and a continuous mastercopy in belt form;

Fig. 5 is a view in vertical section showing a modification;

Fig. 6 is a vertical section through a further modified form of the invention;

Fig. 7 is a view partly in vertical section and partly in side elevation showing the invention shown in Fig. 6 equipped with a flat platen and flat cooperating members;

Fig. 8 is a view in vertical section of a further modification; and

Fig. 9 is a view in vertical section of another modification.

The feeding method used in this invention is produced by bringing the surface of a rotating gelatin belt into contact with a sheet of paper in the paper tray. The paper adheres to the gelatin and is carried to the printing members of the duplicating machine. The gelatin contacts the paper on a line across the gelatin belt where said belt changes from a cylindrical to a rectilinear surface and at an angle which leaves the forward part of the paper free from contact with the gelatin and therefore free to enter between the printing members and to be gripped by them and thereby stripped from the gelatin.

As the paper is carried along the flat surface of the gelatin it remains in alignment and is dampened by its continued contact with the moistened gelatin. The small cylinder on which the gelatin belt rotates may be placed in close proximity to the two printing members at their point of contact, thus enabling the paper to be stripped from the gelatin, which result could not be obtained if the gelatin revolved on one large cylinder that could not be placed in close proximity to the printing members on account of its size. In describing the invention the following terminology may be noted which will be used. The "liquid process" is the method of

making duplicate copies directly from a master copy bearing a reversed image in hectograph duplicating ink, the duplicate copies being made by bringing a dampened portion of paper or cardboard into contact with said reversed image under pressure.

A "liquid hectograph mastercopy" is a sheet of paper or other suitable material having thereon a reversed image in hectograph duplicating ink that will be printed onto a dampened paper or cardboard when said paper or cardboard is brought into contact with the image on said mastercopy.

A "continuous liquid hectograph mastercopy" is a liquid hectograph mastercopy that is not limited in length by the length of the circumference of either printing member or by any condition except what would be impracticable in use. Another form of a "continuous liquid hectograph mastercopy" is a liquid hectograph mastercopy in belt form passing around two or more cylinders.

"Printing members" or a printing couple are those portions of the printing equipment that contact the mastercopy and the paper and force them together under pressure in order to obtain the printed copy. Such printing members or a printing couple may be cylinders or platens, or a flat surfaced member cooperating with a cylinder or flat surfaced members operating one against the other without rotating cylinder action.

A "printing medium" is a flexible sheet of material carrying thereon an image in reverse that may be printed onto cardboard or paper when the latter is brought into contact therewith.

A "gelatin film" is a pliable backing sheet with a covering of gelatin composition. This gelatin composition remains damp and has adhesive quality and absorbs further moisture readily.

Referring to the drawings, particularly Figs. 1 to 3, an apparatus is shown somewhat diagrammatically comprising a frame 10. This frame has standards 10a at either side thereof between which is disposed a cylinder 11. Cylinder 11 is mounted for rotation on trunnions 11a having bearings in frame members or standards 10a. A platen roller 12 is shown journaled between side members of frame 10 on trunnions 12a. A bar 10b projects at opposite sides of each standard 10a and rollers 13 and 14 are journaled between the end portions of members 10b on shafts or trunnions 13a and 14a respectively which will have bearings in members 10b. A crank 15 is shown connected to shaft 13a while a crank 16 is shown connected to shaft 14a. Cranks 15 and 16 have handle portions 15a and 16a of the usual construction attached thereto. Standards 10c project upward at the forward end of frame 10 between which is supported a water reservoir 17. Reservoir 17 has a filling pipe 17a closed by a stopper 17b. A wick 18 is secured in reservoir 17, the same having a portion disposed within said reservoir and having a portion extending therebelow. Wick 18 will extend across the machine for the full length of the roller 12 and cylinder 11. A roller 20 is mounted between the sides of frame 10 on a shaft 21 journaled in said frame and another roller 22 is journaled between uprights 10d at each side of the frame on a shaft 23 journaled in frame members 10d. A continuous sheet 25 of flexible material, such as paper, passes around the lower part of cylinder 11, the same being shown as carried on the roll 13 and as being wound on the roll 14 after passing in

contact with cylinder 11. Another continuous sheet of material 26 such as paper is shown passing between the sheet 25 and platen roller 12, sheet 26 being carried on and unwound from roll 20 and being wound onto roll 22 after passing roller 11. The sheet 25 is in the "liquid hectograph master copy" and the sheet 26 is the sheet or paper upon which the printing is to be done.

Before describing the operation of the apparatus shown in Figs. 1 to 3, it may be stated that in the usual construction of apparatus using the "liquid process" a cylinder and platen revolving with the cylinder quite similar to cylinder 11 and platen 12 are used. The liquid master copy is placed around the cylinder in contact therewith, the same being attached to the cylinder. The cylinder revolves and the master copy revolves with the cylinder. The paper to be printed is dampened just before it is fed between the cylinder and the platen. In passing between the cylinder with the master copy thereon and the platen it comes in contact with the hectograph ink on the master copy under considerable pressure. The moisture on the paper dissolves a sufficient amount of the hectograph ink on the master copy so that the printing operation is performed and a copy is made. With proper adjustment from 300 to 500 copies may be made in this manner from one master copy. The liquid used in dampening the paper is ordinarily of such a chemical nature that it will evaporate very quickly and for this reason this method of duplicating is sometimes called the "spirit process." The "liquid master copy" may be used to make a small number of copies and may then be filed away and later used to make further copies. Short runs may thus be made and these continued until the maximum of from 300 to 500 copies have been made. These copies may be made with considerable time intervening between the different times of imprinting.

In the operation of the device shown in Figs. 1 to 3, the liquid master copy will be prepared as has been above indicated and this will be carried on roll 13 and be rolled up thereon. The paper to be printed will be on roll 20. The master copy will be passed under roll 11 and will be secured to roll 14. The end of the paper to be printed will be carried over roll 12 and between the same and the master copy 25 and will then be connected to roll 22. Roll 14 is then rotated by any suitable means such as the crank handle 16 and roll 22 will be rotated in any suitable manner. A driving connection could be used between rolls 14 and 22 and would preferably be of a type having some slipping motion or lost motion as the frictionally engaging rims 14c and 22c so that the tension would not become too great on either the master copy 25 or the paper 26. As the master copy and paper 26 move together between rolls 11 and 12 the impression will be made on paper 26 so that the matter is printed on paper 26. Wick 18 will be saturated with the desired liquid and will transfer sufficient moisture to paper 26 so that a good impression is obtained. When the entire master copy has been printed it will have been rolled up on roll 14 and the printed paper will be on roll 22. These can then be removed from the rolls and the roll 14 can be interchanged with roll 13 and the printing operation could be repeated with a new roll of paper on roll 20.

In Fig. 4 a modification is shown in which frame 10 is used and on which are mounted the rollers 13 and 14 as well as rollers 20 and 22 as

shown in Fig. 1. In place of the cylinder 11 the frame is arranged with a flat bed surface 27. Below the surface 27 is arranged a printing member or printing means 28 having a flat top surface and adapted to press a sheet against the surface 27. Member 28 is connected to one end of a lever 29 shown as oscillatable about a pivot 29a and having a handle portion 29b. While it is obvious that member 28 could be reciprocated in various ways the structure shown is a simple embodiment of one form which could be used. The structure shown in Fig. 4 also includes the liquid tank 17 and parts as shown in Fig. 1. The master copy 25aa is in belt form and extends around the rollers 13 and 14 and around and in engagement with the surface 27 as shown. The paper to be printed is carried on the roller 20.

In the operation of the device shown in Fig. 4 the continuous master copy 25 passes across the flat bed surface 27 as the master copy unwinds from roller 13. At the same time the dampened paper 26 passes across the flat bed surface 27 as this dampened paper unwinds from roller 20. When the image on the master copy that is to be imprinted is properly located so that it will contact the dampened paper the movement of the master copy and the dampened paper is stopped momentarily and the flat imprinting means 28 forces the master copy and the dampened paper together under pressure and the imprint is made on the paper. There are numerous methods that may be used to force the imprinting means 28 toward the flat bed surface 27 and to regulate the pressure placed on the master copy and the dampened paper as they are forced together. One method is shown in Fig. 4.

After one imprint is made as described, the pressure of master copy against dampened paper is released and the master copy and the paper are moved forward until another image is in position to be imprinted on the dampened paper and then the operation is repeated in the same manner as described.

Different combinations of imprinting means may be used under this method of imprinting from a continuous liquid master copy onto a dampened paper. A very practical combination would be to use a cylinder rotating under pressure against a flat bed surface. This patent specification is not limited to any specific combination of imprinting means.

An advantage of using a master copy in belt form on the rollers, as shown in Fig. 4, is that in this form the master copy does not need to be changed from the receiving roller to the first roller when one complete copy has been made. For this reason the belt form of printing member can be used when the length of copy to be printed is shorter and permits the use of the belt form. When the length of copy to be printed in continuous form is too long to permit the use of the belt then the printing member may be rolled from the first roller and wound onto the receiving roller.

Referring to the device shown in Fig. 5, the same comprises a cylindrical roller 76, the same having a gear 77 secured to one end which meshes with another gear 78 secured to another cylindrical roller 79 having its axis some distance above and at one side of the axis of roller 76. A printing member 80 which will be wound on roller 79 is shown and the same will pass from roller 79 downwardly around a smaller roll 81 and then to roller 76 on which it will be wound.

Roll 81 has a gear 82 secured to one end thereof meshing with another gear 83 secured to one end of a platen roll 84 disposed beneath roll 81. Platen roll 84 in some cases will have a flat portion 84a at one side thereof. At one side of the roll 81 is quite a small roll 86. Roll 86 may be carried on a shaft 85 which will be journaled in bearings in the end plates 90. A much larger roller 87 is mounted at one side of roll 86. It may be stated that the rollers 76 and 79 will be carried on shafts 88 and 89 respectively which will be mounted in bearings in a frame comprising end plates 90, one of which only is shown. Roller 87 will also be carried on a shaft 91 which will be journaled at its ends in the end plates 90. An endless gelatin film 92 extends about the peripheries of rolls 86 and 87. Roll 87 will be rotated by a belt 93 which will run over a pulley formed at one end of roll 81 and over a similar pulley formed at one end of roll 87. A paper-supporting means which may comprise a container having a bottom plate 94 is provided beneath roll 87 on which is supported a plurality of superposed sheets of paper 95. The endless gelatin film 92 is disposed so that it will travel on rollers 86 and 87 in the rotation of the latter and engage the top sheet of the paper 95. A moistening device 97 is provided and this will be disposed above the top run of film 92. This may comprise a liquid-containing receptacle from which projects a brush 97a in engagement with film 92. To keep the sheets of paper 95 in proper relation to the film 92, the paper-supporting means 94 will be constructed and arranged for vertical movement and will be moved upwardly by a weight 99 to which is secured a cable 100 running over pulleys 101 and having its other end attached by an eye bolt 102 to the support 94. Pulleys 101 can conveniently be supported on shafts 103 journaled in bearings in the frame 90. With some type of printing and when printing is to be done on a continuous sheet, roller 84 may be cylindrical. When however a separate sheet of paper is to be printed, if roller 84 were cylindrical there could be no open space between the rollers into which the forward end of the separate sheet of paper could pass before being gripped by the rollers. By providing the flat surface such as 84a on roller 84, the rollers 81 and 84 will be out of contact for a portion of a revolution, thus forming an open space therebetween. Then the separate sheet of paper to be printed can be inserted by the feeding operation through this open space the desired distance and the rollers 55 when they again contact one with the other will then get a firm grip on the paper. The separate sheet of paper will be engaged by the rollers when flat portion 84a passes roller 81 and the separate sheet of paper will then be moved by the rollers as well as by the moving gelatin film and the printing done thereon. The separate sheet of paper will then be discharged after passing between the printing member and roller 84.

In the operation of the apparatus shown in Fig. 5, the printing member 80 will be rolled up on roll 79 with one end thereof secured to roll 76. One of the shafts 88 or 89 will be rotated either by power or by a crank, such as shown in Figs. 1 and 4 and rolls 76 and 79 will move in a counter-clockwise direction. The printing member will thus be wound on roll 76 and will unwind from roll 79 and will pass under the smaller roll 81. If shaft 89 is driven, roll 79 will be driven by roll 76 through the gears 77 and 78. The printing member will rotate roll 81 and this will,

through the gears 82 and 83, rotate platen roll 84. Rotation of roll 81 will, through belt 93, rotate roll 87. The rotation of roll 87 will cause the film 92 to travel around rolls 86 and 87. The outer side of film 92 will be moistened and as said film moves about roll 87 it will engage the top sheet of paper 95 and said sheet will adhere thereto. The top sheet will be moved with the film 92 and will be moved between platen roll 84 and the printing member 80. The paper will be moistened by its contact with film 92 and the paper will thus be printed as it passes beneath printing member 80 and between the rolls 81 and 84. As the paper moves between the member 80 and roll 84 it will be stripped or disengaged from the film 92. It will be noted that the sheet of paper is engaged by film 92 at some distance from its front edge. There will be some overlapping of the sheets of paper, as shown in Fig. 5. This will not be objectionable however as a sheet of paper is never printed very close to the top, which top often contains a heading, such as the name of a firm, etc. Alternately shaft 91 could be driven and this would rotate roll 81 through the belt 93 and roll 81 would rotate the member 89 which in turn would rotate roll 79 and roll 76 would then be driven by gears 78 and 77. As the sheets of paper 95 are removed, the support 94 is moved upwardly by weight 99 so that the paper is kept in proper contact with the film 92. The sheets of paper are thus successively and automatically moved and printed.

In Fig. 6 a roll 104 is shown, similar to rolls 76 and 77. Roll 104 is carried on a shaft 109 which will be journaled in bearings in end plates 111, only one of which is shown. A printing member 112 is wound on roll 104 and as the printing progresses it is unwound from roll 104 and after being printed passes over a small roller 105 carried on a shaft 106 journaled in bearings in end plates 111. A smaller roll 114 is carried on a shaft 115 journaled in end plates 111 and said roll 114 has a gear 116 secured at one end thereof. A gear 116 meshes with a gear 117 secured to one end of a platen roll 118 carried on a shaft 119 which will be journaled in bearings in end plates 111. Quite a small roller 120 is disposed at one side of roller 114 which may be carried on a shaft 121 which will also be journaled in bearings in the end plates 111. A larger roller 123 is carried on a shaft 124 which will be journaled in bearings in the end plates 111. Roller 123 will be formed as a pulley at one end and a belt 125 runs over said pulley and over a pulley formed at one end of roller 120. An endless gelatin film 126 runs over rollers 123 and 120. A crank 128, indicated partly in dotted lines, may be secured to one end of shaft 124. A roll 129 is carried on a shaft 130 which may be journaled in bearings 131 movable vertically in slots 11a in end plates 111. A sheet or strip 132 of paper to be printed will be wound on roll 129 and this paper will pass around the outer surface of film 126 as it passes around and beneath roller 123. A moistening device 134 is provided which will preferably be disposed above the upper run of film 126. Said device may comprise a liquid container from which projects a brush or other absorbent member 134a having contact with film 126.

In operation the shaft 124 may be driven as by the crank 128 and this will cause the gelatin film 126 to travel about rolls 123 and 120 as said rolls rotate in a counter-clockwise direction. The paper 132 will adhere to a certain extent to

film 126 and the same will be moved by said film and directed between mastercopy 112 and platen roll 118. The printing member 112 will of course carry the matter to be printed and this will be printed on the paper 132 which has been dampened by its engagement with the moistened surface of film 126. With the apparatus shown in Fig. 6, a continuous sheet can thus be printed. With the form shown in Fig. 6, a continuous sheet of paper can thus be moved and moistened by the film 126.

In Fig. 7 a modification of the invention illustrated in Figs. 5 and 6 is shown. A platen 135 is used having a flat top surface over which the paper 133 will pass as it is fed by the endless film 126. Film 126 is provided with a moistening device comprising a liquid container 134 and a brush 134a, as shown in Fig. 6. The mastercopy or printing member 80a will pass from a roll similar to roll 79 which will be disposed above and at one side of platen member 135. Platen member 135 has a downwardly extending portion 135a having therein a slot 135b through which passes a pin 136 secured adjacent one end of a lever 137 fulcrumed on a shaft 138. Lever 137 is provided with a handle portion 137a. A member 135 is disposed above member 135 and has a lower flat surface cooperating with the top surface of member 135 in the printing operation.

In operation the paper or sheet 133 to be printed will be fed from a suitable roll, such as roll 131 in Fig. 6, and will pass around under the film 126 and be moved by it over member 135. The printing member 80a will be unrolled from a roll, such as roll 79 and will pass under member 139 and be rolled up on a roller, such as roller 76 shown in Fig. 5. Platen 135 will be reciprocated at intervals and sheet 133 will thus be printed. It will be understood that members 112 and 133 will be intermittently progressed. While platen 135 could be reciprocated by any suitable means, in the embodiment of the invention illustrated it will be raised by the operator pressing down on handle 137a.

Referring to Fig. 8, a side frame 140 of a machine is shown and there will be two of these in laterally spaced relation. A cylinder or roll 141 is carried on a shaft 142 which will be journaled at its ends in suitable bearings in the side frames 140. Cylinder 141 will have a printing member 143 engaging the periphery thereof which may be a liquid hectograph mastercopy. A platen roll 145 is disposed below roll 141 and will be carried on a shaft 146 having its ends journaled in suitable bearings in the side plates 140. A small roller 147 is disposed at one side of rollers 141 and 145 and substantially opposite the space therebetween, which roll 147 will be carried on a shaft 148 having its ends journaled in bearings 60 in side plates 140. A larger roll 149 is provided which may be carried on a shaft 150 also having its ends journaled in suitable bearings in side plates or frames 140. An endless gelatin film 151 extends about the rolls 147 and 149. A moistening device 152 is provided which may comprise a container for liquid and a brush 153 projects from one end of member 152 and will be disposed in contact with film 151. A carrier or container 155 adapted to carry superposed sheets of paper 156 70 is disposed beneath film 151 and the uppermost sheet will be in contact with the lower side of film 151. Carrier 155 will be arranged to be moved upwardly and it will be moved upwardly automatically by a weight 156 carried by a cable 75 or flexible member 157 running over suitable

pulleys 158 which will be mounted on shafts 159 suitably supported from side plates 140. Cable 157 will be connected to carrier 155 in any suitable manner, as by having its end secured to an eye bolt 160 secured in carrier 155. A pulley 162 will be secured at one end of shaft 142 and a crank 163 may be secured to the outer end of shaft 142 at the outer side of one of the side plates 140. A pulley 165 will be secured to one end of shaft 150 and a suitable belt 164 will pass over pulleys 162 and 165.

In operation the paper will be supplied to carrier 155, as shown, and the operator will turn crank 163. This will rotate cylinder 141 and the printing member 143. Roll 149 will be rotated through belt 164 so that the gelatin film 151 will be caused to travel about rollers 147 and 159. Roll or cylinder 141 will be rotated in a counter-clockwise direction, as seen in Fig. 8. The upper sheet of paper 156 will be engaged by the gelatin film 151 and will be moved with said film so that its free end will pass between printing member 143 and platen roll 145 and will thus be printed. The sheets of paper will pass to the right of platen roll 145 and may be received on any suitable support. A film 151 will be moistened by brush 153 to which liquid will be supplied from member 152. The paper will be moistened by its contact with film 151 and the paper will thus be printed as it passes beneath printing member 143. As already described in connection with Fig. 5 the sheet of paper will be engaged by film 151 at some distance from its front edge. The sheets of paper will thus overlap somewhat as they pass between rolls 141 and 145. The sheets of paper on carrier 155 will be moved upward by weight 156 so that the top sheet will always engage film 151. The sheets of paper are thus successively automatically moved and printed.

It will be apparent that the sheets of paper 156 could be carried in a superposed relation or in a stack, as shown, and be disposed above film 151 so that said film would engage the lowermost sheet and move it between the printing members. With such an arrangement the sheets would move down by gravity and the lowermost sheet would be kept in proper contact and proper relation with film 151 or with film 92, as shown in Fig. 8. With such an arrangement any paper-lifting device, as shown in Figs. 5 and 8, would not be necessary.

In Fig. 9 a slightly different form of the invention is shown, the structure comprising side plates 170, in which are journaled the ends of shafts 171, 172 and 173. Rollers 174, 175 and 176 are carried respectively on shafts 171, 172 and 173, and an endless printing member 178, which may be a liquid hectograph mastercopy, runs over the peripheries of said rollers. A platen member 179, shown as in the form of a roller, is disposed below roller 176 and carried on a shaft 180 having its ends journaled in suitable bearings in plates 170. A shaft 181 is provided having its ends journaled in bearings in plates 170 and the same carries a small roller 182. Another shaft 183 has its ends journaled in bearings in plates 170 and has secured thereto a larger roller 184. An endless gelatin film 185 passes around rollers 182 and 184. A liquid container 186 is provided, shown as disposed above the top run of film 185, the same having a brush 187 extending from its upper end and arranged to be in contact with film 185. A crank 188 is secured to the end of one of the shafts 171, 172 or 173, preferably shaft 171 as shown, and a pulley 189 is secured to shaft 171

at one side of printing member 178. A pulley 190 is secured adjacent one end of shaft 183 and a belt 192 runs over pulleys 189 and 190. A roller 193 is carried on a shaft 194 having its ends journaled in bearings 195 vertically slidable in guideways 170a formed in plates 170. Roll 193 is adapted to carry the paper 196 which is to be printed, which paper passes around the outer end of roll 184, film 185 and underneath film 185, the same passing between member 178 and platen 179.

In operation with the parts disposed as shown and described, the operator will rotate crank 188 and this will rotate roll 174. Said crank will be rotated in a counter-clockwise direction, as shown in Fig. 9, and printing member 178 will be moved around rollers 174, 175 and 176. Roller 184 will be driven through belt 192 and pulleys 189 and 190 at substantially the same peripheral speed as the printing member 178. The paper 196 will be unwound from roll 193 and will pass around film 185 and between printing member 178 and platen 179 and will thus be printed. Said paper will be fed by the friction thereof on film 185. Film 185 will be moistened by brush 187 and the paper will thus be moistened so that it can be printed by member 178. As the paper is unwound from roll 193, said roll will move downward, the bearing 195 sliding down in guideways 170a. A printing member in belt form is thus used to print a continuous sheet of paper.

From the above description it will be seen that I have provided a simple and highly efficient printing mechanism and one which will have a high degree of utility in practical use. Where a continuous printing member is used, as in Figs. 1, 5 and 6, a long list of numbers, data, addresses or other information can be carried to be printed on the printed sheet. This arrangement will have a high degree of utility in printing payrolls, menus and similar lists, as well as addressing articles to be mailed. In the form shown in Figs. 8 and 9, a printing member of smaller extent is used and the information thereon can be repeated on the individual sheets or on an endless sheet. The gelatin film is used to feed and move the paper to the printing couple and this film is also utilized for moistening the paper when a hectograph mastercopy is used. As shown, the gelatin film can feed individual sheets of paper or it can feed a continuous length of paper. As shown and described, the individual sheets of paper are automatically moved into proper contact with the gelatin film. The device has been amply tested in actual practice and found to be very successful and efficient. The term "endless" used herein and in appended claims as applied to the master copy and to the continuous sheet on which the matter is printed should be understood as meaning that said members may in a literal sense be in continuous form without connected ends or that it may consist of a strip of material having its ends joined or connected.

This application is a continuation in part of applicant's co-pending application, S. N. 517,545, filed January 8, 1944, on "Method and Apparatus for Printing" which has become abandoned subsequent to the filing of this application.

It will of course be understood that various changes may be made in the form, details, arrangement and proportions of the apparatus and in the steps and sequence of steps of the method without departing from the scope of applicant's invention, which, generally stated,

consists in a method and apparatus capable of carrying out the objects above set forth, such as disclosed and defined in the appended claims.

What is claimed is:

1. A duplicating apparatus having in combination, a frame, a rotary cylinder and platen cooperating under pressure of one toward the other as a printing couple, a printing medium on said cylinder, two rollers with axes substantially parallel to the axes of said printing couple secured to said frame adjacent to said printing couple, an endless gelatin film belt on said rollers, said gelatin film consisting of the whole extent of said belt, said belt engaging said rollers and traveling about the same continuously in the same direction, means for dampening said gelatin film for moistening and feeding paper to said printing couple and means for rotating the said printing medium and the said gelatin film at the same peripheral speed.

2. A duplicating apparatus having in combination, a frame, a rotary cylinder and platen cooperating under pressure of one toward the other as a printing couple, a printing medium on said cylinder, two rollers with axes substantially parallel to the axes of said printing couple secured to said frame adjacent to said printing couple, an endless gelatin film belt on said rollers, said gelatin film consisting of the whole extent of said belt, said belt engaging said rollers and traveling about the same continuously in the same direction, means for dampening the said gelatin film, and means for rotating the said printing medium and the said gelatin film at the same speed, means for supporting sheets of paper to be printed adjacent said gelatin film, whereby said gelatin film may contact successive sheets of paper and carry them between said rotating printing medium and said platen, thereby imprinting said paper from said printing medium, said printing couple forming means for stripping said paper from said gelatin film.

3. A printing machine having in combination, two rotatable rollers cooperating as a printing couple, two spaced cylinders having axes substantially parallel to the axes of said rotating rollers, an adhesive gelatin film belt traveling over and about said cylinders, said gelatin film consisting of the whole extent of said belt, said belt engaging said cylinders and traveling about the same continuously in the same direction, said belt having a planar surface of said gelatin film between said cylinders, means for continuously applying moisture to said gelatin film, means for pressing a sheet of paper against said planar surface of said adhesive gelatin film to dampen said sheet of paper as it adheres to said gelatin film, said paper being advanced by movement of said gelatin film belt, one of said cylinders being adjacent said printing couple and being of small diameter relative to the other whereby said belt makes a sharp turn around said smaller cylinder, said sheet of paper being advanced by said belt to said printing couple and said printing couple acting as a stripping means to strip said sheet of paper from said gelatin film belt.

4. A printing machine having in combination, two rotatable rollers cooperating as a printing couple, two spaced cylinders having axes substantially parallel to the axes of said rotating rollers, a belt traveling over and about said cylinders in one direction, having an outer coating of hectograph gelatin composition thereon,

means for continuously applying moisture to said gelatin coating, means for pressing a sheet of paper against said moistened gelatin to dampen said sheet of paper as it adheres to said gelatin coating, means for rotating said belt continuously in a direction to feed said sheet of paper toward said printing couple, one of said cylinders being adjacent said printing couple and being of small diameter relative to the other whereby said belt makes a sharp turn around said smaller cylinder, said sheet of paper being advanced by said belt to said printing couple and said printing couple acting as a stripping means to strip said sheet of paper from said gelatin, and a continuous hectograph master copy carrying an image in hectograph ink constructed and arranged to pass between the members of said printing couple and into contact with which said dampened sheet of paper is brought by said platen, said printing couple acting simultaneously to print said sheet of paper and strip the same from said gelatin film.

5. In a machine of the class described the combination of a frame, two rotatable rollers operating as a printing couple mounted on said frame, two cylinders having axes parallel to the axes of said rotating rollers, one of said cylinders being adjacent said couple and of small diameter relative to the other, a belt having an outer surface of hectograph gelatin composition and traveling over and about said cylinders and moved thereby, means for continuously applying moisture to said gelatin composition, a supplementary cylinder mounted on said frame adjacent said cylinder with the larger diameter, said supplementary cylinder having a peripheral surface adapted to carry a continuous roll of paper, said supplementary cylinder being disposed so that said continuous roll of paper engages said gelatin composition and adheres thereto so that said paper is dampened by said moistened composition means for rotating said belt continuously in a direction to feed said paper toward said cylinder of small diameter and to said printing couple, said gelatin belt making a sharp turn around said latter cylinder, said printing couple constituting a stripping means adjacent said cylinder of smaller diameter to strip said paper from said gelatin belt.

6. In a machine of the class described the combination of a frame, two rotatable rollers operating as a printing couple mounted on said frame, two cylinders having axes parallel to the axes of said rotating rollers, one of said cylinders being adjacent said couple and of small diameter relative to the other, a belt having an outer surface of hectograph gelatin composition and traveling over said cylinders and movable therewith, means for continuously applying moisture to said gelatin composition, a supplementary cylinder mounted on said frame adjacent said cylinder with the larger diameter, said supplementary cylinder having a peripheral surface adapted to carry a continuous roll of paper, said supplementary cylinder being disposed so that said continuous roll of paper engages said gelatin composition and adheres thereto, means for rotating said belt continuously in a direction to feed said paper toward said cylinder of small diameter and to said printing couple, said gelatin belt making a sharp turn around said latter cylinder, said printing couple constituting a stripping means adjacent said cylinder of smaller diameter to strip said paper from said gelatin belt, and a continuous

hectograph master copy carrying an image in hectograph ink constructed and arranged to pass between the members of said printing couple and into contact with which said dampened sheet of paper is brought by said platen, said printing couple acting simultaneously to print said sheet of paper and strip the same from said gelatin film.

7. A machine of the class described having in combination, a pair of spaced cylinders, a continuous master copy having spaced sections of images in hectograph ink thereon, said continuous master copy passing around and connecting said cylinders and movable therewith, said images on said master copy being in reverse, a pair of rollers having peripheral surfaces with axes extending substantially parallel to the axes of said cylinders respectively, a continuous length of paper engaging the peripheral surfaces of said rollers and movable with said rollers by frictional contact with said cylinders, means for dampening said continuous length of paper, a flat bed surface substantially parallel to the axes of said cylinders, a platen co-operating with said flat bed surface, means for passing said continuous length of paper between said flat bed surface and platen, and means for pressing said paper against said sections and images by means of said flat bed surface and platen co-operating as a printing couple.

8. A duplicating apparatus having in combination, a frame, a rotary cylinder and platen co-operating under pressure of one toward the other as a printing couple, a hectograph liquid master copy on said cylinder, two rollers with axes substantially parallel to the axis of said cylinder, one of said rollers being larger than the other, said other of said rollers being adjacent said cylinder, an endless gelatin film belt on said rollers, said gelatin film consisting of the whole extent of said belt, said belt engaging said rollers and traveling about said rollers continuously in the same direction, said gelatin film belt having a planar surface between said rollers, means for applying moisture to said gelatin film belt, means for supporting a pile of superposed sheets of paper to be printed below said belt and larger roller so that the uppermost sheet engages said belt intermediate the ends of said sheet, the end of said sheet nearest said cylinder being out of contact with said belt, and means for rotating said gelatin film belt continuously in the same direction to move said sheet of paper toward said printing couple, and means for rotating said cylinder and hectograph liquid

master copy at the same peripheral speed as said gelatin film belt whereby said belt will move successive sheets of paper and the forward end of each of said sheets will overlap the rear portion of the preceding sheet and said sheets will

5 be moved on said planar surface of said film to and between said cylinder and hectograph liquid master copy and said platen and will be imprinted from said master copy, said printing couple acting to strip said paper from said gelatin film as said belt makes a sharp turn about the smaller of said rollers.

10 9. The method of feeding a sheet of paper and printing the same by passing the same between a rotating cylinder bearing images in hectograph ink and a platen, which consists in moving an endless adhesive gelatin film in an endless path about spaced rollers, said film being of sufficient length to have a planar surface 15 between said rollers, applying moisture to said gelatin film to increase its adhesive function, bringing a sheet of paper into contact with said planar surface of said film to dampen said paper, moving said paper with said film by the adhesive 20 function of said film, abruptly changing the path of said endless gelatin film adjacent said cylinder to detach the leading edge of said paper from said gelatin film, moving said paper between said cylinder and platen to print said 25 images on said sheet of paper and stripping said sheet of paper from said gelatin film by the engagement of said paper with said cylinder 30 and platen.

FRED R. BARTHOLOMEW.
